ATTORNEY.

UNITED STATES PATENT OFFICE.

HARVEY F. SEYBERT, OF QUEENSTOWN, PENNSYLVANIA.

DRILL-JAR.

SPECIFICATION forming part of Letters Patent No. 592,024, dated October 19, 1897.

Application filed July 2, 1897. Serial No. 643,257. (No model.)

To all whom it may concern:

Be it known that I, HARVEY F. SEYBERT, a citizen of the United States, residing at Queenstown, in the county of Armstrong and State of Pennsylvania, have invented certain new and useful Improvements in Drill-Jars; and I do declare the following to be a full, clear, and exact description of the invention, such as will enable others skilled in the art to which it appertains to make and use the same, reference being had to the accompanying drawings, and to the letters of reference marked thereon, which form a part of this specification.

The special object of the invention is to make a drill-jar with spring-tension, so that there may be a strain on the two members before the jar-heads come together.

Figure 1 of the drawings is an elevation to show the two members coupled together. Figs. 2 and 3 are respectively detail views of the drill and rope sections.

In the drawings, A represents the tool-holder with the longitudinal slots a a' , while B represents the member to the upper end of which the lifting-rope is attached in the usual way. The drill holder or member A receives in the slot a' the plate-spring C, bent alternately in and out or zigzag, so that the openings between the folds will alternate therewith. The

rope section or member B has a slot b , so that it may interlock with the member A by means of the slot a and cause them to be at right angles to each other. The length of the slots a b limit their movement upon one another. 35 On the lower end of the rope section B are pivoted the upper ends of two arms D D, working on the outside of slot a' and having at their lower ends the screws d d , end-threaded to receive the nuts d' d' . D' is an abutment which fits loosely over the threads of the screws. Thus it will be seen that the straining-spring C is held laterally between the arms D D, and vertically between the abutment D' and the upper wall of slot a' , 45 the tension of the spring being regulated by the nuts d' .

What I claim as new is—

In a drill-jar the combination of the two slotted interlocking members A B, the spring 50 C, the arms D D, the abutment D', the screws d , and nuts d' all arranged substantially as shown and described, for the purpose set forth.

In testimony whereof I affix my signature in presence of two witnesses.

HARVEY F. SEYBERT.
